UNITED STATES PATENT OFFICE

BUFORD B. RUSSELL AND SAMUEL PORWANCHER, OF CHICAGO, ILLINOIS, ASSIGNORS
TO DRYING SYSTEMS, INC., OF CHICAGO, ILLINOIS, A CORPORATION OF ILLINOIS

LIFTING HAND TRUCK

Application filed January 9, 1931. Serial No. 507,642.

This invention relates to hand trucks particularly designed for lifting and moving such articles as domestic refrigerators. The truck is designed to be run beneath the article to be moved, and is provided with lifting elements which may be swung to position to engage the frame of said article and then be adjusted upwardly to raise the article vertically while it is firmly resting upon said engaging elements.

Objects of the invention are to provide a light, compact and strong truck with improved lifting and supporting mechanism thereon; to provide lifting means to engage the frame of the article on the inside of the surrounding cabinet apron, and which will not injure the apron or finish of the cabinet, or injure the floor.

The objects of the invention are accomplished by a construction as shown in the drawings, wherein:

Figure 1 is a perspective view of the improved truck, and shows the lifting elements thereof in lifting position.

Fig. 2 is a longitudinal sectional view of the truck, and shows the refrigerator partly broken away and in section thereon.

Fig. 3 is a longitudinal sectional view of the truck, with the lifting elements as they appear before being swung to lifting position, and with the refrigerator shown by broken lines at rest upon the floor.

Fig. 4 is a sectional view of the truck taken on the line 4—4 of Fig. 3.

The truck consists generally of a rectangular frame structure supported upon castors, having inside of and near each of its ends, cross shafts which may be moved vertically in unison. These cross shafts carry yokes for engaging and lifting refrigerators, and which, by oscillation of the shafts may be moved from horizontal position on the truck frame to more or less vertical position for engaging the frame structure of the refrigerator.

The oscillation of the yokes and their supporting shafts is accomplished by means of a longitudinally extending shaft, having a hand wheel at one end and supported on bearings suspended from the cross shafts and

carrying worms for engaging worm wheels on these cross shafts.

The lifting mechanism for the cross shafts includes a plurality of levers having ends extending beneath the cross shafts, and fulcrums on the truck frames, and their opposite ends extend beneath cams or eccentrics. Provision is made for rotating the eccentrics and thereby effect the lifting operation.

Having reference to the drawings, the truck frame 1 is of rectangular form and is supported by a plurality of castors 2 at its corners. At the inner sides of the truck frame, near its ends, are bearings 3 for guiding vertically transverse shafts 4. These shafts are also angularly adjustable within the bearings 3 and carry yoke-shaped lifting elements comprising the arms 5 and transverse cross bars 6. The cross bars 6 are in the form of angle irons in order to fit angle frame members 7, as shown in Fig. 2, on the inside of the refrigerator cabinet 8, beneath the floor 9 thereof.

For the purpose of raising the lifting yokes from the horizontal to a vertical position, the shafts 4 carry worm wheels 10 and 11 with oppositely inclined teeth. Meshing with the worm wheels 10 and 11 are worms 12 and 13 fast to a longitudinally extending shaft 14 rotatable within bearings 15 suspended from shafts 4.

The shaft 14 extends forwardly beneath the truck frame and at its outer end carries a hand wheel 16, by which it is rotated to swing the lifting yokes upwardly or downwardly. The worm gearing serves to retain the lifting yokes in adjusted position. During the lifting operation these yokes are in truly vertical position, or to one side or the other of vertical. This enables use of the device in connection with refrigerators of different sizes, and having the inner frame members 7 spaced more or less apart. When the yokes are swung to position beneath the frame structure of the refrigerator cabinet, the latter may be lifted and lowered thereby by effecting vertical motion of the shafts 4 in the bearings 3. This is accomplished by means of levers 17 having recessed ends 18 extending below the shafts 4. These levers

are fulcrumed on transverse shafts 19 having bearings 20 in the side frames of the truck. The inner ends 29 of the levers 17 curve beneath cams 21 which may be involute disks 5 eccentrically supported fast to a central transverse shaft 22 having bearings in the sides of frame 1.

The shaft 22 carries a bevel gear 23 meshing with gear 24 secured to the inclined shaft 10 25 having bearings in a cross frame member 26, and in a bracket 27 secured to the end of frame 1. An operating handle 28 is secured to the outer end of shaft 25.

In the use of the truck, it is pushed beneath 15 the refrigerator cabinet, as indicated in Figure 3, and then wheel 16 is rotated to raise the lifting members 6 from the full line position to that indicated by dotted lines. The worm gearing on shafts 4 serve to lock the 20 lifting elements in their set position, although such position may not be truly vertical. Then by swinging handle 28 about 180° from the right toward the left, Fig. 1, to the position indicated in this figure, the 25 cams 21 depress the levers 17, thus causing the levers to rock around their fulcrums 19 and raise the shafts 4 and the lifting members thereon. The refrigerator is lifted from the position indicated by the broken lines, 30 Fig. 3, to the position indicated in Fig. 2.

It will be noted that the truck does not 35 protrude much from the cabinet when the latter is supported thereon. This makes it possible to push the cabinet sidewise through the average door opening.

Although but one specific embodiment of 40 this invention is herein shown and described, it will be understood that details of the construction shown may be altered or omitted without departing from the spirit of this invention as defined by the following claims.

We claim:

1. A hand truck comprising a frame structure, lifting elements including cross bars, 45 vertical guides in said frame for the cross bars, a shaft journaled in said frame and carrying cams, means for rotating said shaft, and levers pivotally mounted on said frame and bearing at one end on said cams and 50 extending below said cross bars.

2. A hand truck comprising a frame structure, lifting elements including cross bars, means for raising and lowering said lifting elements, vertical guides in said frame for 55 the cross bars, engaging members projecting from and rigid with said cross bars, means for rocking said cross bars to bring the engaging members into and out of operative position comprising worm gearing including a shaft and bearings for said shaft suspended from said cross bars.

3. A hand truck comprising a frame structure, lifting elements in the form of cross bars and yokes rigid with said cross bars, 60 means for angularly adjusting said lifting 65

elements, and means for raising and lowering said lifting elements.

4. A hand truck comprising a frame structure, vertical guides in said frame, lifting elements vertically movable along said guides, levers pivotally connected with said frame, a shaft journaled in said frame structure, cams on said shaft for operating said levers, means for adjusting said cams, said levers coacting with said lifting elements, 70 said lifting elements being angularly adjustable into and out of operative position, and worm gearing for angularly adjusting said lifting elements.

5. A hand truck comprising a frame structure, vertical guides in said frame, lifting elements vertically movable along said guides, levers pivotally connected with said frame, a shaft journaled in said frame structure, cams on said shaft for operating said levers, means for adjusting said cams, said levers coacting with said lifting elements, 75 said lifting elements being angularly adjustable into and out of operative position, worm gearing for angularly adjusting said lifting elements, and a shaft for operating said worm gearing, said shaft being supported in bearings carried by said lifting elements.

Signed at Chicago this 6th day of January, 1931.

BUFORD B. RUSSELL.
SAMUEL PORWANCHER.
